CLAIM

The ornamental design for a sprayer, as shown and described.

DESCRIPTION

FIG. 1 is a top-front perspective view of our sprayer;

FIG. 2 is another a top-front perspective view thereof;

FIG. 3 is a top-back perspective view thereof;

FIG. 4 is another top-back perspective view thereof;

FIG. 5 is a front view thereof;

FIG. 6 is a back view thereof;

FIG. 7 is a left-side view thereof;

FIG. 8 is a right-side view thereof;

FIG. 9 is a top view thereof; and,

FIG. 10 is a bottom view thereof.

The broken lines represent portions of a spraying device and form no part of the claimed design.

1 Claim, 10 Drawing Sheets
